UNITED STATES PATENT OFFICE.

RALPH SHIPMAN, OF SUNBURY, PENNSYLVANIA.

MEANS FOR PREVENTING SLIPPAGE OF TRACTION-WHEELS.

No. 841,588.

Specification of Letters Patent.

Patented Jan. 15, 1907.

Application filed May 3, 1906. Serial No. 315,011.

To all whom it may concern:

Be it known that I, RALPH SHIPMAN, a citizen of the United States, residing at Sunbury, in the county of Northumberland and State of Pennsylvania, have invented certain new and useful Improvements in Means for Preventing Slippage of Traction-Wheels, of which the following is a specification.

My invention relates to means for automatically regulating the power applied to the traction-wheels of locomotives or other motor-driven vehicles, so as to prevent slippage of the traction-wheels.

By means of my invention the motor may apply full power to the traction-wheels up to the point where slippage of the wheels would occur; but any sudden slippage of the wheels or a slippage in excess of a predetermined amount will result in diminishing the power of the motor to such an extent that further slippage cannot take place.

In carrying out my invention I provide a controlling device for throttling or otherwise varying the power of the motor and means operated by one of the traction-wheels and a truck or trailer wheel for actuating this controlling device to reduce the power of the motor when slippage occurs and to gradually increase the power when the wheels cease to slip.

In the accompanying drawings, which illustrate my invention, Figure 1 is a side elevation of a locomotive having my improvements applied thereto. Fig. 2 is a plan view of the governing mechanism for automatically throttling the steam when slippage of the driving or traction wheels occurs. Fig. 3 is a section on the line 3 3 of Fig. 2. Fig. 4 is a section on the line 4 4 of Fig. 3. Fig. 5 is a side view of a portion of an electric-motor car having my improvements applied to a truck, and Fig. 6 is a plan view of the governing device illustrated in Fig. 5.

Referring to Figs. 1-4, inclusive, of the drawings, A indicates in outline sufficient of a steam-locomotive for the purpose of illustrating my invention. In the pipe 1, leading from the steam-dome of the boiler, is arranged a controlling-valve 2, which is rotatable by means of a rod or stem 3, extending vertically downward through the smoke-box of the locomotive and having secured to its lower end a crank or lever 4. The valve 2 is shown in the rear branch of the fitting 5, which connects the pipe 1 with the branch pipes 6, leading to the steam-chests of the

locomotive, only one of said branch pipes being shown in the drawings. By turning the crank 4 in one direction or the other the valve 2 may be turned so as to throttle the steam passing to both steam-chests or to permit the steam to pass through freely. This valve 2 is operated automatically, so as to throttle the steam flowing to the steam-chests and cylinders whenever the slippage of the driving-wheels exceeds a predetermined amount—that is, in practice the traction-wheels of a locomotive hauling a train of cars will have some slight and practically constant slippage, which may amount to, say, one revolution in twenty, fifty, or a hundred, and it is not desirable to reduce the power applied to the driving-wheels on account of this slight constant slippage which occurs through various causes while the train is in operation under ordinary conditions. In my invention, therefore, the throttle-valve is not operated to reduce the flow of steam for this slight constant slippage, but any slippage which occurs in excess of the slight constant slippage referred to will cause the throttle-valve to immediately throttle the steam to a sufficient extent to stop the wheels from slipping.

The automatic controlling of the throttle-valve 2 is accomplished by the following mechanism: On the axle 7 of one of the pony truck-wheels 8 is secured a sprocket-wheel 9, which is connected by a sprocket-chain 10 to a sprocket-wheel 11, the latter being secured to a counter-shaft 12, arranged parallel with the axle 7 beneath the boiler of the engine in suitable hangers 13, only one of which is shown in Fig. 1. As practically no slippage occurs between the pony truck-wheel and the track T, if the circumferential length of the wheel-tread is, for instance, one hundred inches, the pony truck-wheel will turn once for each one hundred inches of track traversed by the locomotive, and the number of revolutions of the counter-shaft will be directly in proportion to the length of track traversed and its speed will be in direct proportion to the speed of the truck-wheel. A sleeve 14 is loosely mounted upon the shaft 12, and this sleeve has a sprocket-wheel 15 secured thereto and connected to a sprocket-wheel 16 on one of the driving-axles 17 of the locomotive by a sprocket-chain 18. The counter-shaft 12 and sleeve 14 turn in the same direction; but the sprocket-wheels are so proportioned that the shaft 12 rotates at a slightly-greater

speed than the sleeve when the locomotive is operating without slippage of the drivers—as, for instance, where the locomotive is drifting with steam cut off.

5 The shaft 12 has a cam-hub 19 journaled thereon, and this hub has at one end a V-shaped notch or recess 20. A cam-collar 21, splined upon the sleeve 14, so as to rotate therewith and be movable longitudinally thereon, has a wedge-shaped end 22, which fits within the notch or recess in the hub 19. The wedge-shaped end of the collar 21 is normally held within the V-shaped recess in the hub by a spring 23, interposed between the 15 sprocket-wheel 15 and the collar. The inclined faces of the hub and collar form cam-surfaces by means of which any rotation of the hub and collar relatively to one another will cause the collar to move longitudinally 20 upon the sleeve 14 against pressure of the spring 23. Normally the shaft 12 turns faster than the sleeve 14; but a slippage of the traction-wheel will cause the sleeve 14 to move faster than the shaft 12. Means are 25 provided for preventing the hub 19 from moving faster than the shaft 12, and therefore when the sleeve is turned faster than said shaft the hub being held down to the speed of the shaft will cause the collar 21, 30 which turns with the sleeve, to move longitudinally on the sleeve away from the hub. This longitudinal movement of the collar 21 causes a lever 24 to rock about its pivotal point 25. This lever has an elongated eye or 35 slot 26 at its free end, which engages a pin 27 upon the crank 4. It will be seen that any movement given to the lever 24 will cause a movement of the throttle-valve 2, which is connected to the lever by the rod 2 and crank 4. As shown in the drawings, the collar 21 40 has a groove 28, which is engaged by a yoke 24^a on the lever.

In order to permit the shaft 12 to turn freely within the sleeve 14 and hub 19 at a faster speed than said sleeve and hub and yet prevent the hub from being driven at a faster speed than the shaft when slippage of the drivers occurs, and also to arrange the parts so that they will operate the same when the 50 locomotive is moving forward or backward, I provide a pawl P, which has a shank 29 pivoted to the shaft 12 by a pivot-pin 30 and a head 31, which is arranged within a transverse slot 32 in the shaft 12. The shank 29 55 extends longitudinally of the shaft within a groove 33, and its outer edge 29^a is curved, as shown. The head of the pawl has two teeth 34 and 35, adapted to engage ratchet-teeth 36 within the end of the hub 19. A spring 60 37, arranged within a socket in the shaft 12, normally presses the shank of the pawl outward. A sleeve 38 is arranged upon the shaft 12 and movable longitudinally thereon by means of a bell-crank lever 39, a link 40, 65 and a lever and rod 41 and 42, respectively,

the latter being connected to the engineer's reversing-lever 43 in the engine-cab.

In Fig. 1 the engineer's lever is thrown slightly forward of the center, and in this position the sleeve 38 is drawn away from the curved surface 29^a of the shank of the pawl, permitting the tooth 34 of the pawl to engage the ratchet-teeth 36, as shown in Fig. 4.

When the reversing-lever is in the central position, the sleeve 38 is moved part way 75 onto the curved surface of the pawl and presses the head of the pawl into a central position, where neither of the teeth 34 or 35 will engage the ratchet-teeth. When the reversing-lever is thrown back of the center, 80 the spring-tooth 35 on the pawl comes into engagement with the ratchet-teeth. In other words, when the engine is moving forward the pawl-tooth 34 engages the ratchet-teeth at one side of the shaft 12. When the engine is moved backward, the tooth 35 of the pawl engages the ratchet-teeth at the opposite side of the shaft, and when the engine is stopped neither of the pawl-teeth engages the ratchet-teeth. The pawl-tooth 35, as shown 85 in Fig. 4, is movable longitudinally within the head of the pawl and normally pressed outward by a spring 44. The pawl-tooth 34 is arranged to slide over or past the teeth 36 when the shaft 12 is moving faster than the 90 hub 19 in the direction indicated by the arrow in Fig. 4, but to engage the ratchet-teeth 36 when the hub 19 tends to move faster than the shaft in the same direction. Similarly when the engine is reversed the spring-tooth 35 will slip over the teeth 36 when the 95 shaft is moving faster than the hub and both are moving in a direction opposite to that indicated by the arrow in Fig. 4; but if the hub begins to move faster than the shaft and in the same direction the spring-tooth 35 will lock with the ratchet-teeth and prevent the hub 100 from moving faster than the shaft.

In operation when the reversing-lever is thrown forward the collar 38 is moved out of engagement with the shank of the pawl and the tooth 34 on the pawl is yieldingly pressed into engagement with the ratchet-teeth 36 by the spring 37. The shaft 12 will, as before stated, rotate in the direction indicated by the arrow in Fig. 4 at a speed which is proportional to the speed of the truck or trailer wheel 8, by which it is driven, and the number of revolutions of the shaft 12 will be in direct proportion to the length of track traversed. The sleeve 14 and the hub 19 will also rotate in the direction indicated by the arrow in Fig. 4, but at a slightly lower speed than that of the shaft, if no slippage occurs. If a slight constant slippage occurs, such as it 115 is desired to permit without throttling the engine, as may occur when an engine is under way under normal conditions, the hub 19 and shaft 12 may turn at practically the same speed without affecting the operation; 120 125 130

but if a slippage of the driving-wheel B occurs in excess of this predetermined amount the sleeve 14 will be driven faster than the shaft 12. The tooth or dog 34 of the pawl 5 will then hold the hub 19 and prevent it from rotating faster than the shaft 12, thus causing a relative movement between the hub and the sleeve 14. It will be evident that this relative movement will cause the collar 10 21 on the sleeve to move longitudinally upon the sleeve by reason of the cam-surfaces between said collar and the hub. This movement of the collar 21 will rock the lever 24, which in turn will operate the crank 4 and 15 rod 3, thereby turning the controlling-valve 2, so as to throttle the steam. The parts are so arranged that a sudden slippage of the driving-wheel of, say, one-eighth of a revolution will cause the throttle-valve to close to 20 a sufficient extent to prevent further immediate slippage, or a constant slippage in excess of that which occurs under ordinary conditions will result in the gradual throttling of the steam until slippage is prevented. The 25 amount of slippage which may occur without operating the throttle-valve is of course determined by the dimensions of the sprocket-wheels. If the shaft 12 is geared so as to run approximately at the same speed as the 30 sleeve 14, of course the throttle-valve will be operated with very slight slippage; but by increasing the speed of the shaft 12 with respect to the sleeve 14 a greater amount of slippage may occur without affecting the 35 throttle-valve. This is a matter which of course will be adjusted to suit the conditions to be met. When the reversing-lever is moved backward to reverse the engine, the sleeve 38 on the shaft 12 moves along the 40 shank of the pawl and presses the spring-tooth 35 into engagement with the ratchet-teeth in the hub, the tooth 34 being then out of engagement. As the engine will then move backward, the hub and shaft 12 will 45 both move in the opposite direction to that indicated by the arrow in Fig. 4, and it will be seen that as long as no slippage occurs above the predetermined amount the tooth 35 will slip over the teeth 36 or remain sta- 50 tionary with respect thereto; but if slippage above said amount occurs the hub 19 will be pressed by the sleeve 14 against the tooth 35 and the collar 21 and hub will be moved relatively to one another, the former being 55 forced outward by the coöoperating cam-surfaces, as before, thus operating the lever 24 and through said lever the throttle-valve. It will be understood, of course, that the 60 throttle-valve 2 operates entirely independ- 65 ently of the engineer's throttle-valve, and the latter may be left wide open while the engine is in operation.

In starting a load it is well known by those skilled in the art that when the driving-wheels start to slip or lose the rail it requires

some skill on the part of the engineer to regulate the flow of steam so that the engine will pull up to its full capacity without slippage and that after a wheel has started to slip its tractive effort decreases and the wheels will 70 generally make quite a number of revolutions before again catching the rail. This is not only injurious to the locomotive and to the fire in the furnace, which is torn up by the excessive exhaust, but the tractive effort is 75 less when the wheels are slipping than when they are engaging the rail with full power at just below the point of slippage. By means of my invention the throttle will be controlled so that the engine may be worked at its full 80 power up to the point of slippage; but any sudden slippage in starting or in operating the engine or any slippage during operation in excess of the amount which is predetermined by the gearing will immediately throttle the steam to such an extent as to prevent further slippage.

In Figs. 5 and 6 I have illustrated my invention in connection with an electrically-propelled vehicle. Where it is convenient to 90 belt or gear directly from the trailer-wheel axle to the traction-wheel axle, the counter-shaft may be dispensed with, as shown in Figs. 5 and 6. In Fig. 5, C indicates a car-body and D indicates a four-wheeled truck. 95 An electric motor M is suitably geared to the axle 50 of the traction-wheels 51. A sprocket-wheel 16^a upon the traction-wheel axle is connected by a sprocket-chain 18^a to a sprocket-wheel 15^a, which is secured to a 100 sleeve 14, journaled upon the axle 52 of the trailing wheel 53. The sprocket-wheels are proportioned so that the sleeve 14 will turn upon the axle 52 at a slightly lower speed than the said axle and in the same direction. 105 As in Figs. 1-4, inclusive, a collar 21 is splined upon the sleeve and a hub 19 is journaled upon the shaft and a spring 23 normally presses the tapering end 22 of the collar into the notch 20 of the hub. A pawl P 110 operates the same as in the previously-described figures, and a collar 38^a is splined upon the axle 52 and movable to connect either tooth of the pawl with the ratchet within the hub 19, as in said previously-described figures. The lever 26^a, operated by the collar 21, engages the controlling-arm 2^a of a rheostat R or other motor-controlling device for regulating the power of the motor in any well-known manner, not necessary to 115 illustrate. The sleeve 38^a may be shifted when the motor is reversed by mechanically connecting it with the motorman's reversing-switch; but in the drawings I have shown a cam projection 53 upon the sleeve and a 120 guide-rod 54 upon the truck-frame, which engages the cam and moves the sleeve 38^a longitudinally upon the axle when the motor is reversed. In Fig. 6 the sleeve 38^a is 125 shown moved as far as it will go toward the 130

hub 19. If the axle 52 is turning in the direction of the arrow, the rod 54, which is pivoted at 55 to the truck-frame, may swing past the end 53^a of the cam as the latter passes the rod, and a centering-spring 56 always returns the rod to the position shown in the drawing. If now the motor is reversed, it will be seen that the end of the rod will engage the side of the cam which is adjacent to the hub 19, and as the rod only has a limited movement between a pair of stop-pins 57 the sleeve will be drawn in a direction away from the hub 19 and off of the pawl P. Thus the position of the sleeve and of the pawl 15 will be shifted at each change in the direction of movement of the car.

The operation is substantially the same as in the previously-described figures. In Figs. 5 and 6 the lever 26 operates the arm 2^a of an electric controller, while in Figs. 1-4, inclusive, the throttle-valve of a steam-engine is operated by the governor. When the speed of the sleeve 14 increases above that of the trailer-axle 52, the pawl holds the hub 19, 25 and the collar 21 is moved in the direction to cause the controller-arm 2^a to insert resistance in the armature-circuit of the motor or otherwise reduce the power applied to the motor and slippage of the traction-wheels 30 cease. As the car then moves forward on the track without slippage the axle of the trailer-wheels, rotating faster than the sleeve 14, permits the hub 19 to regain its position with respect to the collar, and the spring 23 35 forces the collar 21 back to its original position, thus moving the controller-arm to increase the power of the motor. After this, so long as no slippage occurs, the hub 19 will be driven by the collar 22, but at a slower speed 40 than the axle 52. Whenever slippage increases to an amount determined by the diameter of the sprocket-wheels, the operations will be repeated.

Any wheel that travels upon the track 45 without slippage may be used instead of a truck-wheel to drive one member of the governing device. If desired, the sleeve which carries the sliding collar may be driven from the trailer, and the other member of the 50 governor carrying the pawl may be driven from the traction-wheel, the teeth on the pawl for this change of course being reversed. In such case the gears will be proportioned, of course, so that the member 55 which is driven by the traction-wheel will turn when there is no slippage faster than the member which is driven by the trailer.

I do not intend to limit my invention to the exact arrangement shown in the drawings, as it is obvious that many changes may 60 be made within the scope of my invention.

What I claim is—

1. In a motor-driven vehicle, a motor, a motor-controlling device, a trailing or truck 65 wheel, a traction-wheel, and means operated

by both of said wheels for actuating said device to decrease the power supplied to the motor when the traction-wheel slips.

2. In a motor-driven vehicle, means for preventing slippage of the traction-wheels 70 comprising a controlling device for regulating the power of the motor, and a governor for actuating said device, said governor comprising two members independently driven by a traction and a trailer wheel respectively, 75 and means operated by changes in the relative speeds of said members for actuating said controlling device.

3. In a motor-driven vehicle, means for preventing slippage of the traction-wheels 80 comprising a controlling device for regulating the power of the motor, and a governor for actuating said device, said governor comprising two members independently driven at different speeds by a traction and a trailer 85 wheel respectively, and means operated by changes in the relative speeds of said members for actuating said controlling device.

4. In a motor-driven vehicle, a motor, a motor-controlling device, a trailing or truck 90 wheel, a traction-wheel, and a governor for said controlling device comprising a member driven by the trailer-wheel, a member independently driven by the traction-wheel, means for engaging said members when the 95 relative speeds of said members are materially changed by slippage of the traction-wheel, and means connected with one of said members for actuating said controlling device.

5. In a motor-driven vehicle, a motor-controlling device, a traction-wheel, a trailing wheel, two rotatable members independently driven by the traction and trailing wheels respectively, the member driven by 105 the trailing wheel being arranged to normally rotate faster than the member driven by the traction-wheel, said members comprising means operating by changes in the relative speeds of said members for actuating 110 said controlling device.

6. In a motor-driven vehicle, a motor-controlling device, a traction-wheel, a trailing wheel, two rotatable members independently driven by the traction and trailing 115 wheels respectively, the member driven by the trailing wheel being arranged to normally rotate faster than the member driven by the traction-wheel, one of said members comprising a positively-driven part and a 120 yieldingly-driven part axially movable with respect to one another and having co-operating cam-surfaces, said yieldingly-driven part having means for interlocking with the other of said members when the speed of the slower 125 moving member is accelerated by slippage, and connections between said positively-driven part and said motor-controlling device for operating the latter.

7. In a motor-driven vehicle, a motor-con- 130

trolling device, a traction-wheel, a trailing wheel, two rotatable members independently driven by the traction and trailing wheels respectively, the member driven by the trailing wheel being arranged to normally rotate faster than the member driven by the traction-wheel, one of said members comprising two parts, axially and rotatably movable with respect to one another and having coöperating cam-surfaces, one of said parts being positively driven and the other being yieldingly driven, said latter part having means for interlocking with the other member when the speed of the slower moving member is accelerated by slippage, and one of said parts being operatively connected to the motor-controlling device.

8. In a motor-driven vehicle, a motor-controlling device, a traction-wheel, a trailing wheel, and means for actuating said device to decrease the power of the motor when the traction-wheel slips, comprising two coöperative clutch elements, one rotatable by the trailing wheel, and the other rotatable, at a lower speed, by the traction-wheel, one of said elements being yieldingly driven and the other positively driven, said elements being arranged to interlock when the slower-moving element tends, by reason of slippage of the traction-wheel, to exceed the speed of the faster-moving element, and means coacting with said yieldingly-driven element for actuating the motor-controlling device.

9. In a motor-driven vehicle, a motor-controlling device, a traction-wheel, a trailing wheel, and means for actuating said device to decrease the power of the motor when the traction-wheels slip comprising two coöperative clutch elements, one rotatable by the trailing wheel, and the other rotatable, at a lower speed, by the traction-wheel, one of said elements being yieldingly driven and the other positively driven, said elements being arranged to interlock when the slower-moving element tends, by reason of slippage of the traction-wheel, to exceed the speed of the faster-moving element, and a cam coacting with said yieldingly-driven element for actuating the motor-controlling device.

50 10. In a motor-vehicle, a motor-controlling device, a traction-wheel, a trailing wheel and means for actuating said device to decrease the power of the motor when the traction-wheels slip comprising a clutch element positively driven by one of said wheels, a cam positively driven by the other wheel, a clutch element yieldingly driven by said cam and having a cam-surface coöperating therewith, the parts driven by the trailing wheel being arranged to normally turn faster than the parts driven by the traction-wheel, said clutch elements being arranged to interlock when the slower-moving element, by reason of slippage of the traction-wheel, tends to run faster than the faster-driven element,

and means, actuated by the relative movements of said cam and yieldingly driven member for actuating said motor-controlling device.

11. In a motor-driven vehicle, a motor-controlling device, a trailing wheel, a traction-wheel, a clutch element positively driven by the trailer-wheel, two coöperating cam devices driven by the traction-wheel at a lower rate of speed than said clutch element, one of said clutch devices being positively driven and the other yieldingly driven, the latter having means for engaging said clutch element when the speed of the devices driven by the traction-wheel tends to exceed the speed of the element driven by the trailing wheel and connections between one of said cam devices and the motor-controlling device for actuating the latter.

12. In a motor-driven vehicle, a motor-controlling device, a trailing wheel, a traction-wheel, a clutch element positively driven by one of said wheels, two coöperating cam devices driven by the other wheel, one of said cam devices being positively driven and the other yieldingly driven, the latter having means for engaging the clutch element on the shaft when the relative speeds of the trailing and traction wheels are materially changed by slippage of the latter wheel, and connections between one of said cam devices and the motor-controlling device for operating the latter.

13. In a motor-driven vehicle, a motor-controlling device, a trailing wheel, a traction-wheel, a clutch element positively driven by one of said wheels, two coöperating cam devices driven by the other wheel at a different speed from that of the clutch element, but in the same direction, one of said cam devices being positively driven and the other yieldingly driven, the latter having means for engaging the clutch element on the shaft when the relative speeds of the trailing and traction wheels are materially changed by slippage of the latter wheel, and connections between one of said cam devices and the motor-controlling device for operating the latter.

14. In a motor-driven vehicle, a motor-controlling device, a trailing wheel, a traction-wheel, a shaft positively driven by one of said wheels, a clutch element on said shaft, a sleeve journaled on said shaft, and positively driven by the other wheel, two coöperating cam devices driven by the sleeve, one being positively driven and the other yieldingly driven, the latter having means for engaging the clutch element on the shaft when the relative speeds of the shaft and sleeve are materially changed by the slippage of the traction-wheel, and connections between one of said cam devices and the motor-controlling device for operating the latter.

15. In a motor-driven vehicle, a motor-

- controlling device, a trailing wheel, a traction-wheel, two coacting cam devices driven by one of said wheels, one of said devices being positively driven and the other yieldingly driven, connections between one of said cam devices and the motor-controlling device, a member driven positively by the other of said wheels in the same direction as said cam devices but at a different speed, said member and said yieldingly-driven cam having coacting pawl-and-ratchet mechanism constituting a clutch, arranged to prevent the slower-moving part from exceeding the speed of the faster-moving part, when the traction-wheel slips.
16. In a motor-driven vehicle, a motor-controlling device a trailing wheel, a traction-wheel, two coacting cam devices driven by one of said wheels, one of said devices being positively driven and the other yieldingly driven, connections between one of said cam devices and the motor-controlling device, a member driven positively by the other of said wheels in the same direction as said cam devices but at a different speed, said member and said yieldingly-driven cam having coacting pawl-and-ratchet mechanism constituting a clutch arranged to prevent the slower-moving part from exceeding the speed of the faster part, when the traction-wheel slips, and means for reversing said ratchet mechanism when the motor is reversed.
17. In a motor-driven vehicle, a motor-controlling device, a trailing wheel, a traction-wheel, two coacting cam devices driven by one of said wheels, one of said devices being positively driven and the other yieldingly driven, connections between one of said cam devices and the motor-controlling device, a member driven positively by the other of said wheels in the same direction as said cam devices but at a different speed, said member and said yieldingly-driven cam having coacting pawl-and-ratchet mechanism, constituting a clutch arranged to prevent the slower-moving part from exceeding the speed of the

faster-moving part, when the traction-wheel slips, a reversing-lever for the motor, and means operated by the reversing-lever for reversing the ratchet mechanism.

18. In a locomotive, a throttle-valve, a traction-wheel, a trailing or truck wheel and a governing device actuated by both of said wheels for moving said throttle-valve.

19. In a motor-driven vehicle, a motor-controlling device, a trailing wheel, a traction-wheel, two coacting cam devices driven by one of said wheels, one cam device having a V-shaped notch and the other having a tapering end fitting in said notch, a spring normally pressing said cam devices toward one another, one of said cam devices being positively driven, and the other yieldingly driven, connections between one of said cam devices and the motor-controlling device, and a clutch member positively driven by the other of said wheels and adapted to engage said yieldingly-driven cam, when the relative speeds of the traction and trailing wheels change materially.

20. In a motor-driven vehicle, a motor-controlling device, a traction-wheel and a trailing wheel, a shaft positively driven by one wheel, a sleeve journaled on the shaft and positively driven by the other wheel, a cam splined on the sleeve, so as to rotate with and be movable longitudinally on the sleeve, a cam journaled on the shaft and engaging the cam on the sleeve, a spring normally pressing said cams together, connections between the cam on the sleeve and the motor-controlling device for operating the latter, and a reversible pawl-and-ratchet mechanism between the shaft and the cam which is journaled on the shaft.

In testimony whereof I affix my signature in presence of two witnesses.

RALPH SHIPMAN.
